EYELASH CURLER

William R. Tuttle and William J. Beldue, Rochester, N. Y., assignors to The Kurlash Company, Inc., Rochester, N. Y., a corporation of New York

Application August 7, 1947, Serial No. 767,090

4 Claims. (Cl. 132—32)

1

This invention relates to eyelash curlers, and particularly to those of the type disclosed in our Patent No. 2,391,047 dated December 18, 1945. One of the objects of the present invention is to provide, in an eyelash curler of this character, means for guarding or protecting moving or operative parts of the curler so that these parts cannot come into contact with the skin of the user to possibly scrape or injure the same.

Most eyelash curlers of the character described are provided with a fixed jaw and a movable jaw, between which the eyelash to be curled is gripped, and the movable jaw is usually operated by a link which extends from a movable handle pivotally secured to a fixed handle forming an extension of the fixed jaw. The movable handle is formed with an extended leg projecting beyond its pivot, and the operating link for the movable jaw is pivotally attached to this extended part of the movable handle. When the movable handle is operated, its extended part is swung in an arc beyond the fixed handle, and since the end of this extended part is directed toward the face or cheek of the user, there is the likelihood that the end of this moving part will scrape against the face and scratch or injure the same.

Therefore, one of the objects of the present invention is to provide a structure in which the moving parts of the device, and particularly the extended part of the movable handle and the end of the link attached to the same will be guarded, covered and protected at all times, and the portions of the device which are likely to come into contact with the face will be rounded or arcuate and smooth and immovable, so that during the operation of the device, the possibility of the face or skin of the user being scratched or damaged will be completely eliminated.

More particularly, the invention contemplates the provision of a fixed jaw to which a handle portion is connected, and of a movable jaw slidably mounted on a part of the fixed jaw; the fixed handle being provided with a guard or shield in the form of a channel-shaped housing, projecting from an arcuately shaped part of the fixed handle, and the movable handle being pivotally mounted in said guard or shield and having its projecting end part, and the end of the link which connects to the movable jaw, covered and protected by said guard or shield.

In the accompanying drawing, wherein an illustrative embodiment of the invention is disclosed, Fig. 1 is a side elevation of the improved eyelash curler, with a portion of the movable

2

handle shown fragmentarily, and the curler being in its open position; Fig. 2 is a side elevation of the lower portion of the eyelash curler, with one of the sides or face plates of the guard or shield removed to show construction, and other parts being broken away; Fig. 3 is a sectional view on the line 3—3 of Fig. 1, looking in the direction of the arrows, and Fig. 4 is a front view of the eyelash curler, with parts broken away at the upper and lower ends of the same.

With reference to the drawing, 1 indicates the fixed handle portion of the curler, the same being preferably, but not necessarily, composed of wire, and being formed at one end with the finger-receiving loop 2. At its opposite end, the handle portion 1 is in the form of a yoke, composed of the two spaced rods or posts 3 and 4 on the upper ends of which is secured the curved fixed jaw 5. The upper edge of the fixed jaw 5 is provided with a turned-over portion or bead 6 to thereby provide a smooth surface for contact with the face when the device is operated.

The rods or vertical posts 3 and 4 of the fixed handle portion 1 are provided at a substantially central point with flattened parts 7 and 8, which are arcuately curved forwardly as at 9. Secured between these flattened parts 7 and 8, as by spot welding or by a rivet or pin 10 are edge flanges 23 and 24 formed on a pair of segmental plates 11 and 12. These plates co-operate to form a channel-shaped guard or shield for certain moving parts of the device and also serve to act to pivotally support the movable handle 13 between them.

The movable handle 13 is composed of wire and is provided with the finger loop 14 and at one end is bent laterally, as indicated at 15, this laterally-bent portion 15 being pivoted at 16 between the guard plates 11 and 12, each of these plates having an inwardly-pressed lug portion 17 between which the end 15 of the movable handle is pivoted. Adjacent to its free end, the portion 15 of the movable handle 13 pivotally receives the end of a yoke-shaped link 18 having its upper end attached to the movable jaw 19. Said jaw 19 is in the form of a curved channel member having an insert or facing 20 of soft material, such as rubber, which is brought into contact with the lower edge 21 of the upper jaw when the lower jaw is raised by movement of the movable handle 13 in a direction toward the fixed handle 1. The movable jaw 19 is provided at its opposite ends with the loops 22 which are guided on the upper portions of the rods 3 and 4 of the fixed handle portion.

From the foregoing, the operation of the device will be readily understood. When the curler is being used, it is held in such a position that the arcuately curved portions 9 of the fixed handle portion 1 are directed forwardly toward the face and as these portions of the fixed handle are smooth and rounded and have no movement during raising and lowering of the movable jaw 19 by movement of the handle 13, the face or skin of the user of the device cannot be injured by the end of the part 15 since the same is covered and protected by the guard plates 11 and 12. When the eyelash is inserted between the jaws 5 and 19 and the movable jaw 19 is elevated by movement of the handle 13 toward the handle 1, the eyelash will be compressed between the soft facing material 20 and the lower edge of the upper jaw 5 and will be curled accordingly. It will be noted that during the swing of the handle 13 toward the fixed handle 1, the end portion 15 of the handle 13 is being moved through an arc which is within the confines of the guard or shield, composed of the plates 11 and 12, so that, as a result, this moving end of the movable handle 13 as well as the end of the link 18, is enclosed or housed and cannot contact with the face or skin of the operator.

Having described one embodiment of the invention, it is obvious that the same is not to be restricted thereto but is broad enough to cover all structures coming within the scope of the annexed claims.

What we claim is:

1. In an eyelash curler, a fixed handle carrying a fixed jaw, a guard rigidly attached to the fixed handle, said guard consisting of a pair of spaced segmental plates, a movable handle pivotally mounted between said plates and having a free end portion movable in an arc between said plates, a link having one end attached to said free end portion of the movable handle, and a movable jaw slidable on the fixed handle, the other end of the link being secured to said movable jaw.

2. In an eyelash curler, a pair of handles, one of said handles carrying a pair of spaced plates, the second handle being pivotally mounted between the spaced plates and having an end portion movable in an arc between the plates, the plates being of a size sufficient to cover and protect the end portion of the handle that is pivoted between them, one of the handles being provided with a fixed jaw and the second handle being operatively connected to a movable jaw which is

moved to or from the fixed jaw by pivotal movement of the handle to which it is linked.

3. In an eyelash curler, a fixed handle composed of spaced wires formed at one end into a finger-receiving loop and at the other end into spaced posts, a fixed jaw in the form of a curved plate secured at the ends of said posts, the wires of said handle being flattened and arcuately curved at a substantially central location on the handle, a pair of segmental plates having flanges along one edge located and secured between the flattened portions of the handle, said plates co-operating to form a channel-shaped guard directed rearwardly of the curved portion of the handle, a movable handle pivoted between said plates, said movable handle having an end portion movable in an arc in the space between the plates, the movement of said end portion being limited segmentally to the area defined by the plates, a link pivoted at one end to the end portion of the movable handle, and a movable jaw slidably mounted on the posts of the fixed handle, the second end of the link being attached to the movable jaw.

4. An eyelash curler having a fixed handle carrying a stationary jaw, a movable jaw slidably mounted on the fixed handle, the fixed handle being provided with a channel-shaped housing having spaced walls, a movable handle having an offset end portion pivoted between the walls of the housing, a link having one end connected to the movable jaw and its other end pivotally attached to the offset end of the movable handle, the last-mentioned end of the link and the offset part of the movable handle to which it is attached being movable within the housing in the space between the pivot for said movable handle and the fixed handle, the fixed handle having a curved portion between its jaw and handle portion with the housing secured to said curved portion.
